TIRE UNIFORMITY TESTING MACHINE

Earl L. Bishop, Cuyahoga Falls, Ohio, assignor to The Akron Standard Mold Company, Akron, Ohio, a corporation of Ohio

Continuation-in-part of design application Ser. No. 1,722, Mar. 31, 1966. This application Apr. 19, 1967, Ser. No. 6,749

Term of patent 14 years

(Cl. D54—13)

FIG. I

FIG.2

FIG.3

FIG. 4

FIG. 5

FIG. 1 is a front perspective view of a tire uniformity testing machine embodying my new design;

FIG. 2 is a top plan view of a tire uniformity testing machine embodying my new design;

FIG. 3 is a rear view of a tire uniformity testing machine embodying my new design;

FIG. 4 is an end view looking from the left hand side of FIG. 2 of a tire uniformity testing machine embodying my design; and

FIG. 5 is an end view looking from the right hand side of FIG. 2 of a tire uniformity testing machine embodying my design.

The broken line showing of the tire in FIGS. 1, 2 and 5 of the drawings is for illustrative purposes only.

This is a continuation-in-part of application Serial No. D. 1,722, filed Mar. 31, 1966, now abandoned.

I claim:

The ornamental design for a tire uniformity testing machine, as shown and described.
